UNITED STATES PATENT OFFICE.

HUGH MACKENZIE LESLIE, OF MARIKUPPAM, INDIA.

AUTOMATIC FILTERING-MACHINE.

No. 892,275.

Specification of Letters Patent. Patented June 30, 1908.

Application filed October 22, 1907. Serial No. 398,546.

To all whom it may concern:

Be it known that I, HUGH MACKENZIE LESLIE, a subject of the King of Great Britain, residing at Marikuppam, in the State of Mysoore, Southern India, have invented certain new and useful Improvements in Automatic Filtering-Machines, of which the following is a specification.

This invention has reference to an improved construction of machine for the filtration of pulp and more particularly finely crushed ore or slime under treatment of the cyanid process of gold extraction.

This invention is novel in character and construction especially in so far as it has a series of filters arranged in fixed positions round a centrally arranged and rotatable device (or devices) to which the pulp or slime and wash liquor is applied and thereafter automatically delivered by means of pipes or equivalent to the said filters. Each filter can be automatically charged, washed and discharged the charging and washing being capable also of adjustment to suit the material being filtered.

In order that my said invention may be clearly understood I have hereunto appended, by way of illustration or example, explanatory drawings which show one mode of constructing the apparatus.

Figure 1 is a vertical section taken on the line X, X, Fig. 2. Fig. 2 shows on the right hand side of the central line, a plan view and on the left hand side a horizontal section taken on the line X, Y, Fig. 1. Figs. 3 to 8 are detail views showing how a frame *a* is provided with vacuum and pressure pipe connections. Fig. 9 is a detail front view of one of the chutes 3.

The same reference letters wherever repeated indicate the same parts.

In carrying out my invention I make the machine of a circular shape and I provide it with a series of filtering frames *a* arranged in a circle, each frame being provided with an axle *b* with which it is caused to revolve at suitable intervals by means to be hereinafter described. The frames *a* remain stationary unless when acted on by the aforesaid means.

The ends of each axle *b* are supported in bearings *c*, *c*¹, which latter are supported on inner and outer bars *d*, *d*¹, in a framework *d*², the bars *d*, *d*¹, being arranged concentrically round a centrally situated and vertical shaft *e*. The inner end of each axle *b* is provided

with a tappet wheel *f* having four projecting prongs or teeth *f*¹.

The frames *a* are doubled, that is to say, they have two filtering surfaces *g*, *h*, and they are reversible, so that when one surface has been used and the frame reversed the other surface is turned upwards ready for use. The frames *a* are made of either wood or metal or a combination of both and each side of each frame may be provided with an interior frame *i* wedged or bolted in position and which is covered with a filtering medium preferably cotton or linen duck. The filtering medium is marked *g*¹, *h*¹.

The centrally situated and vertical shaft *e* is supported by a footstep bearing *j* and around this shaft is suitably built up a circular framework *d*² or other like structure which may consist of metal beams *k* of any desired section riveted or bolted together. Tappet arms *l*, *l*¹, are adjustably secured on the shaft *e* in such a position as to strike the prongs *f*¹ of the tappet wheels *f* and so turn over or reverse the frames *a*. The shaft *e* is rotated by suitable gearing from a prime mover. Each frame *a* has, as shown at Figs. 3 to 8 openings *a*³, *a*⁴, which communicate with passages *a*¹, *a*² in a box *a*⁵. These boxes are fixed in position and the passage *a*¹ is supplied with vacuum from the main vacuum pipe *m* by a branch *n* while the passage *a*² is supplied with compressed air (or water under pressure) from a main pipe *p* by the branch *p*¹. The pipe *p* runs round the frame and is provided with branches *p*¹ leading to each frame.

The filtering is effected by means of vacuum from the main vacuum pipe *m* which is supported by the structure *d*². The branch pipes *n* are led from the main vacuum pipe *m* to the frames *a*, and each branch is provided with a controlling valve *o*. By means of its proper valve *o* the vacuum is applied to the filter of each frame which is, for the time being, uppermost and by means of the same valve when the frame is turned about its axis, the vacuum is shut off from this filter. Compressed air (or water under pressure) is supplied to the filter for the time being, at the under side of each frame by the branch pipes *p*¹ which are also provided with controlling valves.

The pulp to be filtered is fed, by any suitable means, into a revolving hopper *q* keyed to a hollow spindle *q*¹ having a flange *r* at its lower end. This flange is secured to the up-

per end of the centrally situated and vertical shaft *e* and between this flange and the bottom of the hopper *q* are one or more hollow wash-rings *s* or chambers. The hollow spindle *q*¹ has holes *t* which communicate with each or all of the hollow wash rings. One (or more) of these latter is provided with a radially extending wash pipe *u* (or pipes) fitted with a controlling valve *v*, the radial pipe 10 communicating with a trough *w* which is divided into compartments *x* corresponding to the number of frames *a*. The wash rings *s* are adjustable on the shaft *e* so that the wash pipes can be adjusted to suit the trough and when adjusted can be fixed by means of a key.

From the revolving hopper *q* the pulp or slime is delivered by means of the radially extending pipe *y*¹ (or pipes) fitted with a controlling valve *l* into the compartments *x* of the circularly arranged trough *w* which is disposed above the frames *a* and supported by means of the angle irons *4*. Each compartment *x* of the trough *w* is provided at the bottom thereof, with an outlet pipe *2* which conveys the pulp into a guiding chute *3* supported by angle irons *4* or the like carried by the structure *d*². The chutes *3* deliver the pulp to their respective frames *a*.

30 The wash rings may be simply hollow cast iron rings placed one above the other. Any suitable number of wash pipes (*u*) can be screwed into these rings (a second pipe is indicated by dotted lines in Fig. 1) thereby multiplying the number of washings given. Further, by using one or more rings and wash pipes the washing can be arranged to suit the class of ore under treatment. Means may be provided for operating the vacuum 40 and compressed air (or water under pressure) valves automatically.

z is a collecting trough into which the washings run.

The *modus operandi* is as follows:—The pulp or slime is supplied continuously to the hopper *q* and runs down the pipe *y* into the compartments *x* of the trough *w* filling the same one after the other as the hopper revolves with the vertical shaft *e*. From the compartments the pulp runs down into the respective chutes *3* and on to the filtering cloth of each filter for the time being uppermost. As the vertical shaft *e* revolves, the wash pipe *u* follows the charging pipe *y* and 55 delivers wash liquor from the wash ring which is continuously supplied with water or other wash liquor through the hollow spindle *q*¹ to each filter in succession so as to wash the same. When the washing has 60 been completed the vacuum is turned on by the valve *o* operated by hand or otherwise and dries the pulp on each filter frame which is thereafter turned over by the action of the projecting arms *l*, *l*', striking the tappets *f*. 65 Just as the filter frame is almost upside down

a puff of compressed air (or water under pressure) is admitted to the frame by its compressed air branch *p*¹. Simultaneously with the admission of compressed air to the filter for the time being undermost the filter 70 for the time being uppermost is brought into communication with the vacuum pipe.

It will be seen that as the pulp and wash liquor is continuously supplied and as the shaft continuously revolves, the filtering 75 operation can be carried on continuously.

Having now fully described my invention what I claim and desire to secure by Letters Patent is:—

1. A filtering machine having, in combination, a series of filters supported in a circle in fixed positions, a centrally situated and rotatable pulp and wash liquor supply, means for rotating the same and means for automatically delivering the pulp and the 80 liquor to the filters.

2. A filtering machine having, in combination, a series of double sided filters supported in a circle in fixed positions, a centrally situated and rotatable pulp and wash 90 liquor supply, means for rotating the same and means for automatically delivering the pulp and the liquor to the filters.

3. A filtering machine having, in combination, a series of double sided and reversible 95 filters supported in a circle in fixed positions, a centrally situated and rotatable pulp and wash liquor supply, means for rotating the same means for reversing the filters and means for automatically delivering the pulp 100 and the liquor to the filters.

4. A filtering machine having, in combination, a series of filtering frames, each frame being double sided and having a filtering medium at each side thereof supported in a 105 circle in fixed positions, a centrally situated and rotatable pulp and wash liquor supply, means for rotating the same means for reversing the filtering frames and means for automatically delivering the pulp and the liquor 110 to the filtering frames.

5. A filtering machine having, in combination, a series of double sided and reversible filters supported in a circle in fixed positions, a centrally situated and rotatable pulp and wash liquor supply, means for rotating the same, means for automatically reversing the filters and means for automatically delivering the 115 pulp and the liquor to the filters.

6. A filtering machine having, in combination, a series of filters supported in a circle in fixed positions, a centrally situated and rotatable shaft, a pulp receptacle on said shaft, a wash liquor receptacle on said shaft, and means for automatically delivering the 120 pulp and the liquor to the filters.

7. A filtering machine having, in combination, a series of filters supported in a circle in fixed positions, a centrally situated and rotatable shaft, a pulp hopper connected 130

with said shaft, a liquid receptacle, a wash ring connected with said shaft and means for automatically delivering the pulp and the liquor to the filters.

8. A filtering machine having, in combination, a series of filters supported in a circle in fixed positions, a centrally situated and rotatable shaft, a hollow spindle surmounting said shaft, a liquid receptacle, a pulp hopper on the spindle, a wash ring on the spindle and means for automatically delivering the pulp and the liquor to the filters.

9. A filtering machine having, in combination, a series of filters supported in a circle in fixed positions, a centrally situated and rotatable shaft, an adjustable pulp hopper connected with said shaft, a liquid receptacle, a wash ring connected with said shaft and means for automatically delivering the pulp and the liquor to the filters.

10. A filtering machine having, in combination, a series of filters supported in a circle in fixed positions, a centrally situated and rotatable shaft, a pulp hopper connected with said shaft, a liquid receptacle, an adjustable wash ring connected with said shaft and means for automatically delivering the pulp and the liquor to the filters.

11. A filtering machine having, in combination, a series of filters supported in a circle in fixed positions, a centrally situated and rotatable shaft, an adjustable pulp hopper connected with said shaft, a liquid receptacle, an adjustable wash ring connected with said shaft and means for automatically delivering the pulp and the liquor to the filters.

12. A filtering machine having, in combination, a series of filters supported in a circle in fixed positions, a centrally situated and rotatable shaft, an adjustable pulp hopper connected with said shaft, a liquid receptacle, adjustable wash rings connected with said shaft and means for automatically delivering the pulp and the liquor to the filters.

13. A filtering machine having, in combination, a series of filters supported in a circle in fixed positions, a centrally situated and rotatable shaft, a pulp hopper connected with said shaft, a liquid receptacle, a wash ring connected with said shaft and pipes for automatically delivering the pulp and the liquor to the filters.

14. A filtering machine having, in combination, a series of filters supported in a circle in fixed positions, a centrally situated and rotatable shaft, a pulp hopper connected with said shaft, a wash ring connected with said shaft, a circular trough divided into compartments, means for discharging the compartments into the filters and means for charging the compartments with pulp and wash liquor.

15. A filtering machine having, in combination, a series of filters supported in a circle in fixed positions, a centrally situated and

rotatable shaft, a pulp hopper connected with said shaft, a wash ring connected with said shaft, a circular trough divided into compartments, chutes for discharging the compartments into the filters, and pipes for charging the compartments with pulp and wash liquor.

16. A filtering machine having, in combination, a series of double sided filters, a circular frame supporting same, axles for the filters, a centrally situated and rotatable pulp and wash liquor supply, means for automatically delivering the pulp and the liquor to the filters, and means for automatically reversing the filters so as to discharge the same.

17. A filtering machine having, in combination, a series of double sided filters, a circular frame supporting same, axles for the filters, a centrally situated and rotatable pulp and wash liquor supply, means for automatically delivering the pulp and the liquor to the filters, tappets on the axles, and means for striking the tappets and reversing the filters.

18. A filtering machine having, in combination, a series of double sided filters, a circular frame supporting same, axles for the filters, a central and rotatable shaft, a pulp receptacle thereon, a wash device therein, means for automatically delivering the pulp and wash to the filters, tappets on the axles and radial arms on the shaft for turning the tappets.

19. A filtering machine, having, in combination, a series of filters supported in a circle in fixed positions, a centrally situated and rotatable pulp and wash liquor supply, means for rotating the same, means for connecting the filters with a vacuum-creating device, means for supplying compressed air to the filters, and means for automatically delivering the pulp and the liquor to the filters.

20. A filtering machine having, in combination, a series of filters supported in a circle in fixed positions, a centrally situated and rotatable pulp and wash liquor supply, means for rotating the same and means whereby each filter can be automatically charged, washed and discharged.

21. A filtering machine having, in combination, a series of filters supported in a circle in fixed positions, a centrally situated and rotatable pulp and wash liquor supply, means for rotating the same, means whereby each filter can be automatically charged, washed and discharged, and means for adjusting the charging and washing to suit the material being operated on.

22. A filtering machine having, in combination, a series of filters supported in a circle in fixed positions, means for automatically charging the filters, means for automatically washing the filters and means for automatically discharging the filters.

23. A filtering machine having, in combination, a series of filters supported in a circle in fixed positions means for automatically charging the filters in succession, means for 5 automatically washing the filters and means for automatically discharging the filters.
24. A filtering machine having, in combination, a series of filters supported in a circle in fixed positions, means for automatically 10 charging the filters in succession, means for automatically, in succession washing the filters and means for automatically discharging the filters.

25. A filtering machine having, in combination, a series of filters supported in a circle 15 in fixed positions, means for automatically charging the filters in succession, means for automatically, in succession, washing the filters and means for automatically, in succession, discharging the filters. 20

In testimony whereof I affix my signature in presence of two witnesses.

HUGH MACKENZIE LESLIE.
